UNITED STATES PATENT OFFICE.

JAMES H. COUPER, OF ATLANTA, GEORGIA, AND WILLIAM L. ALBRIGHT, OF CINCINNATI, OHIO.

DESIGN FOR A KITCHEN-CABINET.

No. 38,425.

Specification for Design.

Patented Jan. 22, 1907.

Application filed December 18, 1906. Serial No. 348,482. Term of patent 14 years.

To all whom it may concern:

Be it known that we, JAMES H. COUPER, residing at Atlanta, in the county of Fulton and State of Georgia, and WILLIAM L. ALBRIGHT, residing at Cincinnati, in the county of Hamilton and State of Ohio, citizens of the United States, have invented a new, original, and ornamental Design for Kitchen-Cabinets, of which the following is a specification.

Reference is had to the accompanying drawing forming part hereof.

In said drawing, the figure is a perspective view of the kitchen-cabinet, showing our new design.

We claim—

The ornamental design for kitchen-cabinet, as shown.

JAMES H. COUPER.
WILLIAM L. ALBRIGHT.

Witnesses for Couper:

ALPHONSE HEUTEL,
R. A. COHEN.

Witnesses for Albright:

JENNIE THOMPSON,
J. D. DE WITT.
